TRACTION TREAD FOR AUTOMOBILE TIRES

Rolf Pfoertner, 2176 E. 28 Ave.,
Vancouver 12, British Columbia, Canada

Filed Mar. 20, 1975, Ser. No. 560,359

Term of patent 14 years

Int. Cl. D12—16

U.S. Cl. D12—154

FIG. 1 is a top plan view of a traction tread for automobile tires showing my new design and broken away to indicate indeterminate length, it being understood that the tread pattern is repeated uniformly throughout its length; and

FIG. 2 is an end elevational view of FIG. 1, it being understood that the opposite end is a mirror image thereof.

The bottom of the traction tread is substantially a mirror image of the top shown in FIG. 1.

I claim:

The ornamental design for a traction tread for automobile tires, as shown and described.
